UNITED STATES PATENT OFFICE.

ALVA M. FREEMAN, OF SPRINGFIELD, OHIO, ASSIGNOR OF ONE-HALF TO
WILLIAM F. McCOMB, OF SPRINGFIELD, OHIO.

RAILROAD-TIE.

No. 796,811.

Specification of Letters Patent.

Patented Aug. 1, 1905.

Application filed April 3, 1905. Serial No. 253,482.

To all whom it may concern:

Be it known that I, ALVA M. FREEMAN, a citizen of the United States, residing at Springfield, in the county of Clark and State of Ohio, have invented new and useful Improvements in Railroad-Ties, of which the following is a specification.

This invention relates to railroad-ties, and has for its objects to produce a comparatively simple inexpensive device of this character which will afford a firm support for the rails, one which may be readily adjusted to vary the track-gage, and one wherein the rails will be firmly but detachably secured to the ties.

With these and other objects in view the invention comprises the novel features of construction and combination of parts more fully hereinafter described.

In the accompanying drawings, Figure 1 is a side elevation of a tie embodying the invention and showing the rails in section in position thereon. Fig. 2 is a top plan view of the same. Fig. 3 is a section through one end of the tie, taken on the line 3 3 of Fig. 2, with the rail omitted. Fig. 4 is a detail top plan view of the rail-engaging devices. Fig. 5 is a detail view of the turnbuckle. Fig. 6 is a plan view showing a modified form of tie end. Fig. 7 is a side elevation of the same. Fig. 8 is a plan view of a slightly-modified embodiment of the invention. Fig. 9 is a section taken through one end of the tie on the line 9 9 of Fig. 8 with the rail omitted. Fig. 10 is a plan view of a form of box to be used at the rail-joint. Fig. 11 is a top plan view of a modified form of a tie end. Fig. 12 is a detail view of a movable clamping-plate employed in the form of device shown in Fig. 8.

Referring to the drawings, it will be seen that the improved tie comprises end portions or sections 1 and a connecting rod or element 2, composed of a pair of sections having their meeting ends adjustably united by means of a turnbuckle 3 in the form of a tubular sleeve in threaded engagement with the sections of the rod 2, the ends of the rod being in threaded engagement with the tie-sections 1, as more fully hereinafter explained.

Each of the sections 1, which are identical in construction, consists, as shown in Figs. 1, 2, and 3, of a metal box 4, having seated therein a rail-supporting member or chair 5, embedded in and maintained in position within the box by means of a filling 6, composed of cement or the like, said filling terminating

at the normally inner end of the section short of the end wall of the casing 4, thereby forming a space or compartment 7 for a purpose which will presently appear, there being formed integrally with the upper face of the chair 5 an outer fixed rail-engaging member or jaw 8, while at the inner edge of the chair there is formed a pair of spaced ears 9, arranged to overhang and spaced from the upper face of the filling 6.

Engaged beneath the ears 9 is a movable rail-engaging member or jaw 10, provided with a slot 11, extended in line with the longitudinal axis of the member 2 and having seated therein a fastening member or bolt 12, firmly embedded in the cement filling 6 and serving in conjunction with the ears 9 to maintain the jaw 10 securely and slidably upon the tie-section, the jaw 10 being provided with a downturned portion or flange 13, disposed within the space 7 and in threaded engagement with the adjacent end of the connecting element 2, whereby rotation of the latter will move the jaws 10 to or from clamping position upon the base-flange of the rail 14.

In practice the rails 14 are seated upon the tie-sections 1, the base-flanges of the rails being first engaged beneath the fixed jaws 8, the element 2 being thereafter manipulated for moving the clamping-jaws 10 into engagement with the flange of the rail for securing the latter in position upon the tie. It is to be observed in this connection that owing to the element 2 being composed of a pair of sections adjustably connected by the sleeve or turnbuckle 3 the latter may be manipulated for varying the length of the element to accord with the desired gage of the track, or, in other words, to vary the space between the rails 14.

In the form of device illustrated in Figs. 8 and 9 the supporting member or chair 5 is omitted and the clamping-jaws attached directly to the cement filling 6, the movable jaw 10' being in this construction maintained in place wholly by the fastening-bolt 11'. In other respects the construction and operation of the device are identical with those above described.

In Figs. 6 and 7 the box or casing 4' to receive the cement filling is of circular form in plan, while in Fig. 10 the box is shown as provided with lateral extensions 15, thus to afford a firm support for the meeting ends of a pair of rails at the rail-joint.

In Fig. 11 the box or casing 16 is of lesser

width than the boxes 4 and 4' and is formed with the top and bottom walls omitted, thus producing a shell which receives the filling 6.

From the foregoing it is apparent that I produce a comparatively simple inexpensive device which in practice will admirably perform its functions to the attainment of the ends in view, it being understood that minor changes in the details herein set forth may be resorted to without departing from the spirit of the invention.

Having thus described the invention, what is claimed as new is—

1. A rail-tie including an end section consisting of a box or casing having a cement filling, rail-engaging jaws carried by the section, one of said jaws being movable, an element connected with the movable jaw and op-

erable for moving the latter to and from clamping position.

2. A rail-tie comprising end sections, fixed clamping members carried by said sections, movable clamping members operatively engaged with the sections and designed to coöperate with the fixed members for holding the rails, a connecting element extended between the sections and operatively engaged with the movable clamping members, said element being operable for actuating the movable clamps.

In testimony whereof I affix my signature in presence of two witnesses.

ALVA M. FREEMAN.
